B. JORGENSEN

SHOE TRIMMING MACHINE

Filed Dec. 6, 1923

UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-TRIMMING MACHINE.

Application filed December 6, 1923. Serial No. 679,040.

This invention relates to trimming machines and more particularly to machines used in the manufacture of shoes to trim surplus material from the bottoms of lasted 5 shoes before the soles are laid.

One well-known type of shoe is made with a canvas upper and a rubber outsole, and the latter is secured to the bottom of the lasted shoe by vulcanization without any 10 stitching or other fastening means except that an adhesive is used to hold it prior to and during the vulcanizing operation. In a shoe of the type mentioned the insole has a smooth bottom surface since adhesion 15 and vulcanization are relied upon exclusively to form a union between the sole and the upper. Incidentally to lasting a shoe of this type the overdrawn marginal portion of the upper is temporarily fastened to the 20 insole by adhesion, and although care is exercised to keep said marginal portion as smooth as possible it is impossible to avoid forming pleats or crimps where the upper is lasted around the toe.

25 A satisfactory bond between the outsole and the upper cannot be obtained by vulcanization unless the bottom of the lasted shoe is smooth and even, and it is therefore necessary to trim the crimped or pleated portions flush with the actual bottom of the 30 shoe before the outsole is laid. Heretofore it has been the practice to perform this trimming operation either by hand or with a buffing machine, but hand work is 35 too slow to be economical, while a buffing operation is both too slow and productive of unsatisfactory results.

In view of the foregoing considerations 40 an object of this invention is to provide an improved machine for trimming surplus overdrawn upper material that lies against the face of the insole of a lasted shoe, and more especially one adapted to trim off the pleats or crimped portions of a canvas upper 45 secured to the bottom face of the insole by an adhesive, to put the shoe in satisfactory condition for a rubber outsole to be vulcanized thereto.

It is difficult to trim textile materials with 50 a single cutting edge, but the character of the shoe under consideration is such that it is impossible to operate satisfactorily with shearing members. This condition is met

by that feature of the invention that comprises a power-operated knife arranged to 55 execute a drawing cut, and a shield arranged to be engaged by the bottom of the shoe to control the closeness of trimming and yet to permit the knife to trim the 60 pleated portions of the upper flush to the actual bottom of the sole.

Another feature of the invention consists in organizing the aforesaid knife and shield to be relatively adjustable for the purpose of regulating the closeness of trimming. 65 Still another feature consists in a novel combination comprising the aforesaid shield and means for guiding the shoe by engagement with its perimeter. As shown, the shield and guiding means are fixed relatively one to the other and adjustable as one, so that when the shield is adjusted to cover or uncover certain portions of the knife, as desired, the guiding means will partake of said adjustment and therefore 70 remain in constant relation to the shield. Consequently, as it becomes necessary to adjust the shield to compensate for grinding the knife to sharpen it the guiding means 75 will necessarily receive a corresponding adjustment and the operative will have the advantage of substantially constant operating conditions.

Another feature comprises a novel guard 85 formed and arranged to protect the work and the operative's fingers from injury by the trimming knife, and at the same time to afford an unobstructed view of the operating portion of the knife. As shown, this guard is of skeleton construction and is 90 formed of a single length of rod or wire bent to suitable shape. It is preferably arranged to stand normally in front of the cutting portion of the knife where it functions as a barrier to arrest the shoe or the 95 operative's fingers in case of frontal approach, but is movably mounted so that once the shoe has been placed in a safe position for operation it will be readily deflected and displaced by the surplus portions of material approaching the knife and will remain in contact with the work or so close to it as to continue to safeguard the operative's fingers.

100 Other features of the invention are hereinafter described and claimed and are illus- 105

trated by the accompanying drawing in which,—

Fig. 1 is a perspective view of a trimming machine and a portion of a lasted shoe in operative relation thereto;

Fig. 2 is a top plan view including the trimming knife, the grinding wheel, the toe portion of a lasted shoe in operative position, and the guards partly broken away;

Fig. 3 is a perspective view partly in section and looking upwardly toward the trimming knife and the elements adjacent thereto; and

Fig. 4 is a vertical section of the mounting for the grinding wheel.

The frame 10 of the machine is formed with an overhanging arm 11 in which separate journals 12, 12 are formed to provide bearings for a vertical cutter shaft 13. A disk knife 14 is fastened to the lower end of the shaft and the latter is held against endwise movement by a collar 15 arranged between the journals 12, 12. A pulley 16 is fastened to the upper end of the shaft, and a driving belt 17 is guided thereto by idle pulleys 18, 18 mounted at the rear of the frame. The upper marginal portion 19 of the knife is beveled to provide a sharp cutting edge.

A segmental guard 20 is provided with a hub 21 and this is fastened to an extension of the lower journal 12 by any suitable means such as a set-screw 22. This guard overhangs the trimming knife and is provided with a depending flange 23 that surrounds the major portion of the cutting edge, a relatively small portion of the guard being cut away to expose the operating portion of the knife as shown by Figs. 1 and 2. The hub of the guard 20 is bored at diametrically opposite points to receive the end portions 25, 25 of an auxiliary guard 24 which may be made of a loop of relatively heavy wire. That portion of the guard 20 that overlies the trimming knife serves to support the auxiliary guard in a substantially horizontal position but permits the auxiliary guard to be raised by the work. The auxiliary guard is so formed as to afford an unobstructed view of the trimming locality from above. The end portions 25, 25, which constitute trunnions, are free to turn in their bearings formed in the hub 21 so that the outer portion of the auxiliary guard may be lifted by the work.

As shown by Fig. 3, a segmental shield consisting of a thin plate 26 is arranged under and contiguous to the trimming knife, to guard against cutting the insole while permitting the knife to trim the lumps flush. This shield, which controls the closeness of trimming, is preferably mounted so that it may be adjusted forward and back and also sidewise to cover and uncover portions of the knife, as desired. As shown, it is supported by, and rigidly fastened to, a block 32 on

the rear side of which is formed a dovetail portion 27. The latter is clamped adjustably in a correspondingly formed portion of a holder 28 which is split by a kerf 29 and provided with a clamping bolt 30. The front face of the block 32 is formed to provide two spaced abutments 31 which are arranged below the level of the cutting edge of the knife 14 to be engaged by the perimeter of the shoe to guide the latter. The space between the abutments 31 is preferably just wide enough to receive the toe of the shoe when the heel end swings from one side to the other. The shield-holder 28 is mortised into a portion 33 of the frame and is fastened to the latter by a clamping bolt 34. A slot 35 extending from front to rear affords adjustment of the holder relatively to the frame, while the dovetail portion 27 and the correspondingly formed portion of the holder afford adjustment of the shield from side to side. Vertical adjustment of the trimming knife is afforded by loosening the collar 15, the latter being provided with a set-screw 36 to engage an elongated spot 37 on the shaft 13.

The lasted shoe shown by Figs. 1 and 2 comprises a canvas upper 38 and an insole the bottom face 39 of which is usually coated with a suitable adhesive such as a quick-drying cement. The marginal portion 40 of the upper, which may also be coated with adhesive, has been secured to the face 39 of the insole by the adhesive. As a result of the lasting operation the marginal portion of the upper becomes crimped, and the lumps 41 produced thereby require to be trimmed off to make the bottom smooth and even before the rubber outsole is laid.

In using the described machine to trim off the lumps 41 the operative holds the shoe bottom up and usually begins to trim at or near the ball portion by holding the shoe so that the heel is to the left and the toe to the right. The trimming knife rotates continuously at high speed and trims off the lumps with a drawing cut as the operative moves the shoe from right to left while holding the perimeter of the shoe against the abutments 31 and the overdrawn marginal portion of the upper against the under side of the shield 26. When the toe end of the shoe reaches the trimming locality the operative swings the heel end toward himself and at the same time from left to right. The material to be trimmed passes under the auxiliary guard 24 and also under the flange 23 of the fixed guard 20, the auxiliary guard rising, if necessary, to pass over the lumps 41. The auxiliary guard therefore offers no appreciable resistance to the feeding and manipulation of the shoe since it is made of round wire and is not only smooth but so light as not to be felt. At that stage of the trimming

when the heel end of the shoe is swinging from one side to the other the toe end may enter the recess between the abutments 31, the effect of the recess being to arrest or retard the feeding motion temporarily or until the position of the shoe has been nearly if not entirely reversed. As the opposite side of the forepart is moved into contact with one of the abutments 31 it retracts the toe end from the recess so that the perimeter of the shoe may thereafter slide on both abutments. As shown by Fig. 2, the lumps have been trimmed from one side of the shoe, while the pleats 41 form lumps that have still to be trimmed. The notches 42 are the result of trimming off the pleated portions that form the lumps. The closeness of trimming is controlled by the shield 26 which is engaged by the trimmed marginal portion 40 and is preferably adjusted so that only a relatively narrow portion of the trimming knife is permitted to have contact with the work. When the shield is adjusted to uncover more of the cutting portion of the knife closer trimming is possible, since the shoe may be rocked as much or as little as desired incidentally to its manipulation.

The work-engaging portion of the guard 24 stands initially at or below the level of the knife, and in case the operative presents the work too high this guard arrests the work positively and thereby prevents the knife from cutting the perimeter of the shoe. The operative can therefore present the work only by first passing it under the guard and then raising it to the necessary level, but since this manipulation would usually place a portion of the shoe under the knife, if not also under the flange 23 and shield 26, it insures immunity of the shoe from damage by the knife.

A shaft 50 journaled in a bearing sleeve 51 carries a grinding wheel 52 for sharpening the cutter 14. The sleeve 51 is supported by trunnions 53, 53 in a yoke 54. The yoke is fastened to the base of the frame 10. The trunnions are preferably capable of holding the sleeve frictionally in any position to which it may be tilted, and for this purpose they are screwed into the yoke and are provided with conical ends which occupy sockets formed in the sleeve as shown by Fig. 4. The axis of the grinding wheel is substantially at right angles to that of the cutting knife, and the periphery of the grinding wheel is arranged to grind the beveled marginal portion 19. Referring more particularly to Fig. 2, the angular relation between the line of travel of the knife at the point of contact and the axis of the grinding wheel is such that rotation of the knife induces relatively slow rotation of the grinding wheel, thus equalizing the wear on the wheel. The greater

component of grinding movement is executed by the knife while the lesser component is executed by the grinding wheel. So long as the grinding wheel is in contact with the trimming knife it will continue to rotate under the influence of the latter, but it will not follow automatically as the knife is ground away because the frictional trunnions have sufficient holding effect to sustain the weight of the wheel.

The work required of the knife for the particular purpose described demands a sharp cutting edge at all times, and it is therefore necessary to use the grinding wheel frequently but only for a very few seconds at any one time. Consequently it is desirable to maintain the grinding wheel in proximity to the cutting knife so that no time will be lost in moving it to and from operative position. In practice it is sufficient if the grinding wheel is retracted one eighth or even one sixteenth of an inch from the knife when the latter is sharp enough for trimming. The operative has merely to bear down slightly on the left-hand end of the sleeve 51 to separate the grinding wheel from the knife, the frictional trunnions thereafter sustaining the wheel out of contact with the knife until the right-hand end of the sleeve is depressed. A stop-screw 55 is screwed through a split clamping portion 56 of the yoke 54 to limit the retractive movement of the grinding wheel by arresting downward movement of the left-hand end of the sleeve 51. A bolt 57 serves to tighten the clamping portion 56 to hold the screw 55 from turning accidentally. The screw 55 may also be used to force the grinding wheel against the trimming knife.

Having thus described my invention, what I claim as new and desire to secure by Letters Patent of the United States is:

1. A machine of the character described, comprising a rotary disk-knife arranged to trim lumps from the overdrawn marginal portion of an upper lying on the insole of a lasted shoe, and a shield arranged in contiguous relation to the body of the knife to bear on the trimmed part of said marginal portion.

2. A machine of the character described, comprising a rotary disk-knife arranged to trim lumps from the overdrawn marginal portion of an upper lying on the insole of a lasted shoe, and a stationary shield arranged in contiguous relation to the body of the knife to bear on the trimmed part of said marginal portion.

3. A machine of the character described, comprising a rotary disk-knife arranged to trim lumps from the overdrawn marginal portion of an upper lying on the insole of a lasted shoe, and a thin shield arranged in contiguous relation to the body of the knife

to bear on the trimmed part of said marginal portion, said shield being adjustable transversely of the axis of said knife to cover more or less of the marginal portion of the knife at the trimming locality.

4. A machine of the character described, comprising a power-operated knife arranged to trim lumps from the overdrawn marginal portion of the upper lying on the bottom of 10 a lasted shoe, and a guard arranged in confronting relation to the face of the knife to control the closeness of trimming by engaging the trimmed area of the work.

5. A machine of the character described, 15 comprising a power-operated knife arranged to trim lumps from the over-drawn marginal portion of the upper lying on the bottom of a lasted shoe, and a stationary guard arranged to lie between the knife and 20 said marginal portion to control the closeness of trimming by engaging said portion, said guard and said knife being relatively adjustable to regulate the closeness of trimming.

6. A machine of the character described, 25 comprising two spaced abutments arranged to be engaged by the perimeter of a lasted shoe to guide the latter, a cutter arranged to trim surplus material from the bottom of the shoe adjacent to the points of contact 30 with said abutments, mechanism for operating said cutter, and means arranged to engage the bottom of the shoe to control the closeness of trimming.

7. A machine of the character described, 35 comprising two spaced abutments arranged to be engaged by the perimeter of a lasted shoe to guide the latter, a cutter arranged to trim surplus material from the bottom of the shoe adjacent to the points of contact 40 with said abutments, mechanism for operating said cutter, and a guard arranged to lie between said cutter and the shoe to control the closeness of trimming by engaging the bottom of the shoe.

45 8. A machine of the character described, comprising a trimming knife having a cutting edge for trimming surplus material from the bottom of a lasted shoe, means for moving said knife lengthwise of its cutting edge, a thin plate supported in confronting relation to said knife and arranged to engage the bottom of the shoe to control the closeness of trimming, and means arranged to engage the perimeter of the shoe to guide 50 it relatively to the knife.

9. A machine of the character described, 60 comprising means for trimming surplus material from the bottom of a lasted shoe, adjustable means arranged to control the closeness of trimming by engagement with the bottom of the shoe, and adjustable means arranged to guide the shoe by engagement with its perimeter, the latter two of said means being connected to partake of 65 one adjustment.

10. A machine of the character described, comprising means for trimming surplus material from the bottom of a lasted shoe, means arranged to guide the shoe by engagement with its periphery, and means 70 supported by said guiding means and arranged to control the closeness of trimming by engagement with the bottom of the shoe.

11. A machine of the character described, comprising means for trimming surplus 75 material from the bottom of a lasted shoe, means arranged to control the closeness of trimming by engagement with the bottom of the shoe, and means arranged to guide the shoe by engagement with its perimeter, one 80 of the latter two of said means being adjustable and the other being supported thereby to partake of its adjusting movement.

12. A machine of the character described, comprising means for trimming surplus 85 material from the bottom of a lasted shoe, means arranged to control the closeness of trimming by engagement with the bottom of the shoe, and means arranged to guide the shoe by engagement with its perimeter, 90 said controlling means being adjustable to regulate the closeness of trimming, and said guiding means being connected to said controlling means to partake of its adjusting movement. 95

13. A machine of the character described, comprising means for trimming surplus material from the bottom of a lasted shoe, and an adjustable unit including a shield arranged to control the closeness of trimming 10 by engagement with the bottom of the shoe, and two spaced abutments arranged to guide the shoe by engagement with its perimeter. 105

14. A machine of the character described, comprising means for trimming surplus material from the bottom of a lasted shoe, a member arranged to guide the shoe by engagement with its perimeter, and a shield supported by and projecting from said guiding member to control the closeness of trimming by engagement with the bottom of the shoe, said guiding members being adjustable to regulate the closeness of trimming by adjusting said shield relatively to said trimming means. 11

15. A machine of the character described, comprising a work-rest for engaging the perimeter of a lasted shoe, a shield projecting from said work-rest to bear on the overdrawn portion of the upper lying on the marginal 12 portion of the insole, and a cutter arranged to trim pleats from the bottom of the shoe adjacent to said shield.

16. A machine of the character described, comprising a mechanically operated cutter 12 arranged to trim surplus material from the bottom of a lasted shoe, and a guard arranged to stand normally in front of said cutter to prevent a frontal presentation of the shoe to the cutter, said guard being dis- 12

placeable by the work if the latter be presented otherwise than frontally to the cutter.

17. A machine of the character described, comprising a mechanically operated trimming cutter under which the trimmed work passes, and a guard arranged to stand normally in front of the cutting edge of said knife, said guard being displaceable by the work.
18. A machine of the character described, comprising a cutter arranged to trim surplus material from the overdrawn marginal portion of an upper lying on the insole of an inverted lasted shoe, and a guard arranged to prevent the operative's fingers from touching said cutter, said guard being also arranged to rest on and ride over said surplus material and being movable by the work to avoid hindering manipulation of the latter.

19. A machine of the character described, comprising a cutter arranged to trim pleats from the overdrawn marginal portion of an upper lying on the insole of an inverted lasted shoe, means formed and arranged to prevent the operative's fingers from touching said cutter elsewhere than at the trimming locality, and a guard arranged to prevent the fingers from touching said cutter at the trimming locality, said guard being also arranged to rest on the surplus material and to yield to the demands of its irregularities.

20. A machine of the character described, comprising a stationary frame, a shaft journaled therein and arranged to rotate about a substantially vertical axis, a disk-knife carried by said shaft and arranged to trim pleats from the overdrawn marginal portion of the upper lying on the insole of a lasted shoe, and means arranged to prevent the operative's fingers from touching the edge of the knife while they present and manipulate the shoe in contact with the knife, said means being formed to afford an unobstructed view from above the knife of the working portion of the latter.

21. A machine of the character described, comprising a disk-knife arranged to rotate about a substantially vertical axis to trim pleats from the overdrawn marginal portion of the upper lying on the insole of a lasted shoe, a stationary support, and a knife-guard consisting of a loop of wire the end portions of which are journaled in said stationary support to serve as trunnions, said guard being arranged to bear on the work and turn on said trunnions according to the demands of the work.

22. A trimming machine comprising a substantially vertical driven shaft journaled in a fixed support, a disk-knife carried by said shaft and arranged to trim upper material lying against and adhering to the face of the insole of an inverted cement-lasted shoe, and a guard arranged adjacent to said knife to protect the operator's fingers from being cut while manipulating the shoe in engagement with said knife.

23. A machine of the character described, comprising a knife formed and operated to execute a drawing cut and arranged to trim lumps from the overdrawn marginal portion of an upper on the bottom of a lasted shoe, and a thin shield arranged in confronting relation to the body of said knife to engage the trimmed part of the work, the cutting edge of said knife being in front of the front edge of said shield.

24. A trimming machine comprising a substantially vertical driven shaft journaled in a fixed support, a disk-knife carried by said shaft and arranged to trim upper material lying against and adhering to the face of the insole of an inverted cement-lasted shoe, and a work-rest arranged below the level of the cutting edge of said knife to engage the perimeter of the shoe to guide it relatively to said knife.

In testimony whereof I have signed my name to this specification. 90

BERNHARDT JORGENSEN.
